Primary Examiner — Andrew Kerr*Assistant Examiner* — Courtney Clark-Rasheed(74) *Attorney, Agent, or Firm* — WOMBLE BOND DICKINSON (US) LLP**CLAIM**

I claim the ornamental design of a drinkware, as shown and described.

DESCRIPTION

FIG. 1 is a front, left, top perspective view of a drinkware showing our new design;

FIG. 2 is a front, left, bottom perspective view thereof;

FIG. 3 is a left side view thereof;

FIG. 4 is a right side view thereof;

FIG. 5 is a front view thereof;

FIG. 6 is a rear view thereof;

FIG. 7 is a top plan view thereof; and,

FIG. 8 is a bottom plan view thereof.

The broken lines in the drawings depict portions of the drinkware that form no part of the claimed design.

1 Claim, 7 Drawing Sheets# US D1,016,563 S
